DISHWASHING MACHINE

James E. Elkington, San Francisco, Calif.

Application August 23, 1933, Serial No. 686,431

1 Claim. (Cl. 198—221)

This invention relates to dish washing machines, and particularly to those in which cleansing is accomplished by spraying fluid under pressure.

5 The object of my invention is to provide a dish washing machine including a casing, within which a pair of spraying pipes are rotatably mounted above and below the dishes to be cleansed, said pipes being connected to a power driven pump, and to means for oscillating said pipes back and forth, to equalize the distribution of the fluid spray over the dishes.

Another object of my invention is to provide means for simultaneous oscillation of the spraying pipes and intermittent advancing of the trays 15 loaded with dishes to be cleansed.

Another object of my invention is to generally simplify the dish washing machine and make it superior in point of efficiency and inexpensiveness 20 of construction and operation.

In this specification and the annexed drawings, the invention is illustrated in the form considered to be the best, but it is to be understood that the invention is not limited to such form, because it 25 may be embodied in other forms; and it is also to be understood that in and by the claim following the description, it is desired to cover the invention in whatsoever form it may be embodied.

In the accompanying three sheets of drawings: 30 Fig. 1 is a perspective view of my dish washing machine.

Fig. 2 is a plan section taken through Fig. 3 on the line 2—2.

Fig. 3 is a vertical cross section taken through 35 Fig. 2 on the line 3—3.

Fig. 4 is an enlarged plan view, partly in section, of the spray pipe oscillating mechanism taken on the line 4—4 of Fig. 5.

Fig. 5 is a vertical cross section taken through 40 Fig. 4 on the line 5—5.

Fig. 6 is a side elevation of the spray pipe, partly shown in section.

Fig. 7 is a cross section taken through Fig. 6 on the line 6—6.

Fig. 8 is a plan view of a conveying mechanism 45 in a dish washing machine.

Fig. 9 is a cross section taken through Fig. 8 on the line 9—9.

Fig. 10 is a side elevation of a dog employed 50 in connection with my conveying mechanism.

Fig. 11 is a plan view of an overload release mechanism, partly shown in section.

The dish washing machine of my design comprises a casing 1 supported by four standards or 55 legs 2. A platform 3 is attached to said legs and

carries a tank 5, an electric motor 7, and pump 8, and an oscillating mechanism 9, the last two being driven by said motor.

The casing 1 comprises an enclosure having two doors 11 on opposite sides thereof, slideable vertically in the slides 12. A horizontal trackway 13 is formed of angle bars 14 extending from one door to the other, and having their ends supported by the walls of the casing 1. The trackway 13 serves as a guide for dish racks 10 15 which are passed thru the casing.

A horizontally disposed spray pipe 16 is arranged near the top of the casing 1 above the trackway 13, and is connected by means of an elbow 17 and a pipe 18 to a vertical pipe 19, 15 placed adjacent the wall of the casing. A similar horizontally disposed spray pipe 20 is arranged below the bottom of the trackway 13 and is connected by means of an elbow 17' and a pipe 18' to the pipe 19, said pipe communicating with the 20 discharge side of the pump 8.

The upper spray pipe 16 directs the streams of suds or water downwardly, and the lower pipe 20 upwardly, against the dish rack 15 and against the dishes or articles in said carrier. 25

The bottom partition 22 of the casing 1 extends horizontally through the length thereof and is inclined downwardly toward one side of the casing. The partition 22 covers approximately two thirds of the bottom and merges into a vertical wall 23 of the tank 5, the top of which is covered by separate drainer screen baskets 25 to facilitate the removal and cleansing thereof. One side of the baskets 25 rests on a supporting bar 26 attached to the wall of the tank, and the 30 other side is supported by means of a margin 27 formed on the basket, on the bottom partition 22. 35

The fluid sprayed upon the dish racks 15 passes the strainers 25, leaving the insoluble particles and dirt thereon, and collects in the tank 5, 40 which is connected by a suitable conduit with the intake of the pump 8.

The motor 7 drives the oscillating mechanism 9 by means of a motor shaft 30 supported by a bearing 31 arranged in a casing 32 of the mechanism 9. A worm 33 is affixed on the shaft 30 and meshes with a worm gear 35 carried by and rotating with a shaft 36, which is rotatably supported by the casing 32 and a cover 37. The gear 35 carries an eccentric 39, which is confined with 45 in a yoke 40 adapted to move about a shaft 41, to which said yoke is secured. The comparatively slow rotation of the gear 35 causes the eccentric 39 to impart oscillating motion to the yoke and its associated vertically disposed shaft 50 55.

41. The shaft 41 is rotatably supported by the casing 32 and the cover 37 and is extended through a fluid tight bearing 43 in the partition 22 to protect the oscillating mechanism 8 and the motor 7 from water leakage in the casing 1. The shaft 41 extends upward through the casing 1 and is journaled in a bearing 45 at the top thereof. The shaft 41 carries the arms 47 and 48, in spaced relation thereon.
- 10 Both arms 47 and 48 carry identical mechanisms for the purpose of oscillating the spray pipes 16 and 20 respectively, and a description of but one will be made. Each arm has an adjustable link 50 universally attached thereto, said link 50 having its other end attached to the respective spray pipes.

Each of the spray pipes 16 and 20 consists of two separate tubes 55 having spray nozzles 56 longitudinally spaced on one side thereof. The nozzles 56 are in alignment and are elongated to produce flat overlapping jets of fluid. The cylindrical portion 58 of the elbows 17 and 17' is interposed between the nozzle tubes 55 and is kept in alignment therewith by means of two rings 59 placed over the abutting ends thereof. The rings 59 are rotatable on the portion 58 but are affixed to the nozzle tubes 55 by means of screws 60. Integral with the rings 59 are the ears 62 to carry a shaft 64. The shaft 64 has its center section between the ears 62, of larger diameter than the opposite end sections 65, to maintain the rings 59 in predetermined spaced relation on, but to allow a free rotation of said rings about the portion 58. Nuts 67, screwed onto the opposite threaded ends 66 securely lock the ears 62 to the shaft.

The shaft 64 carries a sleeve 67' which has as an integral part thereof, a stub-shaft 69. The latter serves as a pivot for attachment of the other end of the link 50. The upper part of the stub-shaft 69 is threaded to receive a nut 70 for holding the link 50 in place. The oscillating movement of the shaft 41, through the levers 47 and 48 and associated therewith links 50, is therefore imparted to the spray pipes 16 and 20.

The dishes or other articles to be washed are placed into the dish racks and the latter are moved into the casing 1. The doors 11 are slid down and the motor 7 started. The latter drives the pump 9, which sends the fluid up the pipe 19 to the spray tubes 16 and 20. The oscillating mechanism rocks said spray tubes and the fluid forced from the nozzles 56 is thereby directed and spread over the dishes. The pressure of the fluid is such that it washes all the dirt and waste off the dishes.

In dish washing machines of a larger size, I provide an automatic conveying means for the dish carriers, which is shown in detail in Figs. 8 to 11. It comprises a trackway 75 formed of angle bars 76 supported by brackets 77 which are affixed to the walls of the casing 1.

The brackets 77 also support a pair of bars 78 adapted to slide back and forth upon bracket extensions 80. The bars 78 carry sets of dogs 81 adapted to engage tooth racks 82 attached to the bottom of the dish racks 15'. The mechanism which I employ to actuate the bars 78 consists of a lever 84 which is an integral part of a lever 48' adapted to oscillate the spray pipe and is affixed to the oscillating shaft 41'. The lever 84 carries a link 85, the other end of which is connected to the overload release mechanism 87. The latter consists of a hollow casing 90, having an open end 91, on both sides of which half-circular grooves 92 are formed. A member 93, having cylindrical portions 94 resting in said grooves 92, is yieldingly urged against the casing 90 by a spring 96, one end of which is affixed to the member 93 and the other to the adjusting bolt 97. The casing 90 is affixed to a cross-bar 98 which, with a bar 99, keeps the bars 78 in spaced relation.

The reciprocating motion of the bars 78 operates the dogs 81 and moves the dish carriers 15' in a direction to the discharge door of the casing.

When a dish rack jams to cause an overload on the motor, the member 93 of the overload release mechanism 87 swings about the cylindrical portions 94 as pivotal points, and the reciprocal motion of the bars 78, and consequently the advance of the dish carriers 15', ceases.

Having thus described this invention, what I claim and desire to secure by Letters Patent is:

In a dishwashing machine, a casing; parallel tracks arranged lengthwise of said casing for supporting dish racks thereon; guides beneath each of said tracks; a slide in each guide beneath each track, each slide being held in its respective guide by the overlying track; both sides being held together in fixed relation, being movable in unison on a fixed horizontal plane and in a longitudinal direction relative to the tracks; dogs pivotally mounted on the sides of said slides at spaced points throughout the length thereof, said dogs being movable above and below the horizontal plane of the tracks to engage and disengage the dish racks on said tracks in accordance with the movement of the slides.

JAMES E. ELKINGTON.
